US00D951114S

(12) **United States Design Patent** (10) **Patent No.:** **US D951,114 S**
(45) **Date of Patent:** **** May 10, 2022**

(54) **RADAR**

(71) Applicant: **AUTEL INTELLIGENT TECHNOLOGY CORP., LTD.**,
Guangdong (CN)

(72) Inventor: **Ming Gao**, Guangdong (CN)

(73) Assignee: **AUTEL INTELLIGENT TECHNOLOGY CORP., LTD.**,
Shenzhen (CN)

(**) Term: **15 Years**

(21) Appl. No.: **29/774,382**

(22) Filed: **Mar. 16, 2021**

(30) **Foreign Application Priority Data**

Sep. 28, 2020 (CN) 202030585564.2

CLAIM

The ornamental design for a radar, as shown and described.

DESCRIPTION

FIG. 1 is a front elevational view of a radar showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof; and,

FIG. 8 is a second perspective view thereof.
